UNITED STATES PATENT OFFICE.

EDWARD M. MOLLER, OF JERSEY CITY, NEW JERSEY.

DOOR OR GATE OPERATING MECHANISM FOR THE PLATFORMS OF CARS.

1,079,713.

Specification of Letters Patent.

Patented Nov. 25, 1913.

Application filed August 31, 1912. Serial No. 718,066.

To all whom it may concern:

Be it known that I, EDWARD M. MOLLER, a citizen of the United States, residing at Jersey City, in the county of Hudson and 5 State of New Jersey, have invented certain new and useful Improvements in Door or Gate Operating Mechanism for the Platforms of Cars; and I do hereby declare the following to be a full, clear, and exact description of the invention, such as will enable others skilled in the art to which it appertains to make and use the same, reference being had to the accompanying drawings, and to characters of reference marked 10 thereon, which form a part of this specification.

This invention relates, generally, to improvements in mechanism for opening and closing a plurality of doors or gate-sections, 20 such as are usually located in the side-openings of the vestibules of street railway cars.

The invention has for its principal object to provide a novel and easily actuated mechanism for opening and closing a plurality of 25 foldable doors or gate-sections located in the side openings of the vestibules of street railway cars.

Other objects of this invention not at this time more particularly enumerated will be 30 clearly understood from the following detailed description of the present invention.

With the various objects of the present invention in view, the invention consists, primarily, in the novel door or gate-closing 35 and opening means for the platforms of railway cars hereinafter set forth; and, the invention consists, furthermore, in the novel arrangements and combinations of the various devices and parts, as well as in the details 40 of the construction of the same, all of which will be more fully described in the following specification, and then finally embodied in the clauses of the claim which are appended to and which form an essential 45 part of this specification.

The invention is clearly illustrated in the accompanying drawings, in which:—

Figure 1 is a diagrammatical vertical longitudinal sectional representation of one end 50 of a railway car and its platform, showing in connection therewith and in elevation, and also in their closed relation to the vestibule platform, two sectional doors or gates, and one form of mechanism for simultaneously operating the doors or gates, all illustrating one embodiment of the principles 55 of the present invention; and Fig. 2 is a diagrammatical horizontal sectional representation of a portion of the one end of the car and a portion of the platform thereof, 60 said view showing in plan or top view, the said doors or gates in their closed relation, and the mechanism for simultaneously operating said doors. Fig. 3 is a detail vertical cross-sectional representation, said section 65 being taken on line 3—3 in Fig. 2. Figs. 4 and 5 are enlarged detail views, showing in side view certain parts of the door or gate-opening and closing mechanism. Fig. 6 is a vertical cross-section taken on line 70 6—6 in said Fig. 2, looking in the direction of the arrow α ; Fig. 7 is a vertical sectional representation, taken on line 7—7 in said Fig. 2; and Fig. 8 is a similar section taken on line 8—8 in said Fig. 2, said Figs. 6, 7 75 and 8, all being made on enlarged scales.

Similar characters of reference are employed in all of the above described views, to indicate corresponding parts.

Referring now to the several figures of 80 the drawings, the reference-character 1 indicates a portion of the body of any usual type of street railway car which is provided at one or both ends with the usual inclosed or vestibule-platform 2 and the usual side-step 85 3 leading from the platform. The framework of the vestibule is provided upon that side of the platform 2 at which the step 3 is located with a large side-opening which, under normal conditions, is closed by the 90 hinged and foldably disposed sections or members 4 and 5, and 6 and 7 of a pair of doors or gates.

As shown in Fig. 1 of the drawings, at suitable points in the flooring of the platform 2 are a pair of socket-like bearing-members 8 and 9, and in vertical alinement with said bearing-members 8 and 9 and suitably secured to the upper projecting portion 10 of the frame-work of the vestibule, above 100 the said large side-opening hereinabove mentioned, are a pair of bearing-brackets 11 and 12. Oscillatory mounted in said bearing-member 8 and the bearing-bracket 11 is a vertical rod 13, and oscillatory arranged in said bearing-member 9 and the bearing-bracket 12 is another vertical rod 14, said rod 13 having suitably secured thereto, by means of attaching plates 15, which are fastened to said rod 13 by means 105 of pins 16, the said door-section or member 4. The door-section or member 5 is foldably

connected with the said door-section or member 4, by means of suitable hinges, as 17, and as clearly indicated in Fig. 1 of the drawings. In like manner, there is secured to the previously-mentioned rod 14, by means of attaching plates 18, which are fastened to said rod 14 by means of pins 19, the previously-mentioned door-section or member 7, said door-section or member 7 being foldably connected with the door-section or member 6 by means of suitable hinges, as 20.

As has been stated, the main purpose of this invention is to simultaneously cause the oscillatory or rotary movements of the vertical rods 13 and 14, whereby the doors or gates are also simultaneously opened; and to accomplish this, the mechanism for operating the said rods will presently be more fully described. In operating the said rods 13 and 14, the door or gate-sections 4 and 7 are moved from their closed positions inwardly upon the platform of the car into their opened positions, and in order that the respective door-sections 4 and 5, and 6 and 7, will break joints, and that the section 5 will fold upon the section 4, and the section 6 will fold upon the section 7, suitable guiding means in the form of two bars 21 and 22, arranged in front of the portion 10' of the frame-work beneath the projecting portion 10 and directly above the side-opening of the platform, is provided, the said bars 21 and 22 being suitably secured in place by means of suitable fastening devices or brackets, as 23 and 24. The door-sections or members 5 and 6 have secured thereto, at their upper corners, suitable plates 25, each plate 25 being provided with a stud or post 26, and a guide-roller 27, said post and roller being movably disposed in the guide-space formed between said bars 21 and 22. The action of these rollers 27 is to cause the respective door-sections or members 4 and 5, and 6 and 7 to become folded, when the rods 13 and 14 are rotated so as to bring said door-sections into their open positions with relation to the platform of the car; but, said rollers 27 serving also to cause the several door-sections or members to assume their straightened-out relation, when the said rods 13 and 14 are rotated in the opposite directions. If desired, in alignment with the vertical closing joint formed by the two door-sections or members 5 and 6, there may be a dividing post, as 28, said post being arranged upon the platform 2, near the side-opening, by having its lower end-portion arranged in a socket 29 and its upper end-portion in a socket-like bearing-portion 31 of a bracket 30 which is secured to and extends inwardly from the portion 10 of the frame-work, substantially as illustrated in Fig. 3 of the drawings.

Having in the foregoing described the

general arrangement of the door or gate-sections for closing the exit and entrance-openings thus provided by the dividing post 28, I will now describe one form of mechanism for simultaneously operating all of said door or gate-sections, so as to move them into their open relation, or from their open relation into their closed relation. This door or gate-operating mechanism comprises a suitable shaft or spindle 32 which is rotatably mounted in the bearing-portions of suitable bearing-brackets 33 and 34 which are suitably secured upon the inner front portion of the vestibule frame 35. As shown in Fig. 1 of the drawings, the said vertical shaft or spindle 32 is mounted in the upper half of the platform-space, so as to be out of the way, and said shaft or spindle being provided upon its lower end-portion with a suitable crank-lever or arm 36 for turning said shaft or spindle and which is under easy control of the motorman or other operator stationed upon the platform of the car. As shown more particularly in Figs. 4 and 6 of the drawings, the upper end-portion of the said vertical shaft or spindle 32 extends through the bearing-portion 37 of the bracket 34 and through a bearing-portion, as 39, of a buffer-plate 38 which rests upon the upper surface of the shelf-like member 40 of the bracket 34, and is suitably secured thereto by means of a bolt 41, or other suitable fastening means. The said plate 38 is provided with an upwardly extending flange-like member, as 42, which is provided with an arrangement of stops 43 of a suitable flexible material, against which certain parts of the mechanism are brought into contact, so as to limit the rotary movement of the shaft or spindle 32 in either direction. Resting upon the shelf-like member 40, and mounted upon said shaft or spindle 32, is a collar 44 and secured upon the tapered portion 45 of said shaft or spindle 32 is a crank-arm or link 46, the parts being rigidly connected by means of a washer 47 and a nut 48 which is firmly screwed down upon the screw-threaded end 49 of said shaft or spindle 32. Upon its opposite end-portion the said crank-arm or link 46 is provided with an upwardly extending cylindrical stud or pin 50. Suitably mounted upon the upper tapered end-portion 51 of the door or gate-carrying rod 13 which extends above the bearing 11 is the bearing-hub 53 of a laterally extending plate 52, said plate being provided with guide-flanges 54, and a perforation, as 55, and an elongated hole 56. The bearing-hub 53 of said plate 52 is rigidly affixed upon the end-portion 51 of the rod 13 by means of a washer 57 and a nut 58 which is firmly screwed down upon the screw-threaded portion 59 of said rod 13, substantially as shown in Fig. 7 of the drawings. Adjustably ar-

115

120

125

130

ranged between the guide-flanges 54 of said plate 52 is a plate-like member or element 60, said member or element 60 being formed with a perforation 61 in alignment with the 5 elongated hole 56 and with an elongated hole 62 in alignment with the perforation 56, the member or element 60 being secured in its adjustable relation upon said plate 52 by an arrangement of bolts 63 and nuts 64, or other 10 suitable fastening means. Upon its opposite free end-portion, the said member or element 60 is made with a hub-like enlargement, as 65, which is provided with an upwardly extending cylindrical stud or pin 66. Piv- 15 tally arranged between and connected with the previously-mentioned cylindrical stud or pin 50, and the said cylindrical stud or pin 66 is a suitable adjustable connecting rod, said rod comprising three members 67, 68 20 and 69.

The member 67 is formed upon its one end with a perforated hub 70 by means of which it is pivotally arranged upon the pin or stud 50, being secured upon said pin or stud 50 25 by means of a pin 71, or other suitable fastening means. Upon its other end-portion, the said member 67 is made with an internally screw-threaded socket-like portion 72. The member 68 is formed upon its one end 30 with a perforated hub 73 by means of which it is pivotally arranged upon said pin or stud 66, being secured upon said pin or stud 66 by means of a pin 74, or other suitable fastening means. Upon its other end-portion, the said member 68 is also made with 35 an internally screw-threaded socket-like portion 75. The member 69, hereinabove mentioned, is in the form of a connecting rod and is provided with the right and left-hand 40 screw-threaded end-ports 76 and 77 which are screwed into the respective and correspondingly internally screw-threaded socket-like portions 72 and 75 of the respective members 67 and 68. Thus it will be 45 evident, that after the various parts of this mechanism have been properly adjusted and secured in their assembled relations, by turning the vertical shaft or spindle 32 in either direction, the door or gate-carrying 50 rod 13 is also correspondingly rotated and the door or gate-sections 4 and 5 are brought into their opened or closed relations, as will be clearly evident.

Referring now once more to Figs. 4 and 55 6 of the drawings, it will be seen that there is secured by means of a pin 78, or other suitable fastening means, upon the said vertical shaft or spindle 32, at a point suitably below the bearing 37 of the shelf-like mem- 60 ber 40 of the bracket 34, a sleeve-like member 79, said member 79 having a tapered portion 80 and a screw-threaded part 81. Mounted upon the tapered portion 80 of said member 79 is the hub 83 of a crank- 65 arm 82, said hub 83 being suitably affixed

to said member 79 so as to turn with the latter and with the shaft or spindle 32 by means of a lock-nut 84 which is screwed upon the screw-threaded portion 81. Upon its opposite end, the said crank-arm 82 is 70 made with a hub-like enlargement, as 85, which is provided with a cylindrical stud or pin 86. Pivotaly mounted upon said stud or pin 86, and against accidental displacement therefrom by a pin 87 is a per- 75 forated hub 89 of a plate-like member or rod 88, said rod or plate-like member 88 being provided upon its opposite end-portion with an internally screw-threaded socket-like part or member 90. Suitably 80 secured to a portion 91 of the car-body is a plate 92 from which extend a pair of bearing-arms 93 and 94 provided at their free end-ports with bearings, as 95. Mounted in said bearings 95 are the ends of 85 a short stem or rod 96, indicated in dotted outline in Fig. 5 of the drawings, said rod 96 being fixed in place against displacement from said bearings 95 by pins 97, or other suitable fastening means. Rotatably 90 arranged upon said rod 96, between the said two bearings 95, is a sleeve 98 with which is suitably connected and from which extends laterally a plate 99, similar in construction to the previously-mentioned plate 52, and provided with suitable guide-flanges 100. Adjustably arranged between the guide-flanges 100 of said plate 99 is a plate-like member or element 101, said member or element 101 being adjustably secured to said plate 99, in the manner of securing the plate-like member or element 60 to said plate 52, by an arrangement of bolts 102 and nuts 103. The opposite end-portion of said adjusting plate-like element or member 101 is provided with an upwardly extending cylindrical bolt or pin 104 with which is pivotally connected against accidental displacement therefrom by means of a pin 105, the 105 perforated hub 107 of a rod or plate-like member 106. Upon its opposite end-portion, the said rod or plate-like member 106 is provided with an internally screw-threaded socket-like portion 108. The reference-character 109 indicates a long connecting rod which is provided with the right and left-hand screw-threaded end-ports 110 and 111 which are screwed into the respective and correspondingly internally screw-threaded socket-like portions 90 and 108 of the plate-like members or rods 88 and 106. Suitably connected with and extending laterally from the upper portion of said sleeve 98 is another crank-arm 112, said arm being provided upon its free end-portion with a cylindrical stud or pin 113. Pivotaly connected with said stud or pin 113, and against accidental displacement therefrom by a pin 114, is a crank-arm 115 which is provided upon its opposite free end- 115 120 125 130

tion with an internally screw-threaded socket-like portion 116.

Referring now more particularly to Fig. 8 of the drawings, it will be seen that the door or gate-carrying rod 14 has suitably secured upon its upper end-portion, by means of a pin 117 or other suitable fastening means, the hub-like portion 119 of a crank-arm 118, said arm 118 being formed upon its other end with an enlargement, as 120, which is provided with an upwardly extending cylindrical stud or pin 121. Pivotally connected with said stud or pin 121, against displacement therefrom by a pin 122, is the hub-like portion 124 of a member 123 which is provided upon its opposite free end-portion with an internally screw-threaded socket-like member 125. Connecting the said screw-threaded socket-like portions 116 and 125 is a connecting rod 126 which is provided with the right and left-hand screw-threaded end-portions 127 and 128 which are adapted to be screwed into the respective and correspondingly internally 20 screw-threaded socket-like portions 116 and 125 of the respective members 115 and 123.

From the foregoing description of these last-mentioned parts, it will be clearly evident, that after these various parts of this mechanism have been properly adjusted and secured in their assembled relations, by turning the vertical shaft or spindle 32 in either direction, the door or gate-carrying rod 14 is also correspondingly rotated, and the door or gate-sections 7 and 6 are brought into their opened or closed relation; and, it will be further understood, that by the single turning operation of the said vertical shaft or spindle 32, all the door or gate-operating mechanisms and devices are actuated simultaneously, so that the door-sections or gates are all brought into their opened or closed positions at the same time. It will also be seen, that all the several parts of the mechanisms and devices are placed in the upper portion of the vestibuled platform, out of the way of the persons passing onto or from the platform, but are still within easy reach of the workman, so that any part of the mechanism can readily be repaired, when necessary. Furthermore, there being no parts of the mechanism beneath the platform of the car, where they are subjected to dirt and wet, and flying particles of dust and stones, the mechanism is not likely to get out of order, or difficult to operate on account of the bearings and joints located beneath the car becoming quickly clogged with dirt and dust.

I am aware that changes may be made in the general arrangements and combinations of the several devices and parts, as well as in the details of the construction of the said parts, without departing from the scope of the present invention as set forth in the fore-

going specification, and as defined in the clauses of the claim which are appended to said specification. Hence, I do not limit my present invention to the exact arrangements and combinations of the several devices and parts as described in the said specification, nor do I confine myself to the exact details of the construction of the said parts, as illustrated in the accompanying drawings.

I claim:

1. Mechanism for opening and closing a plurality of foldable doors, comprising a pair of brackets, a vertical shaft mounted in said brackets, a crank-lever upon the lower end-portion of said shaft, and mechanism 75 connected with the upper end-portion of said shaft for simultaneously operating said door or gate-sections, consisting of a crank-arm 80 affixed to said vertical shaft, a pair of adjustably connected plate-like members connected with one of said door or gate-sections, a connecting rod between said crank-arm and said adjustably connected plate-like members, a second crank-arm affixed to said vertical shaft, a third bracket, a second pair 85 of adjustably connected plate-like members pivotally connected with said last-mentioned bracket, a connecting rod between said last-mentioned crank-arm and adjustably connected plate-like members, a third crank-arm also pivotally connected with said last-mentioned bracket, another crank-arm connected with another one of said door or 90 gate-sections, and a connecting rod between said two last-mentioned crank-arms, substantially as and for the purposes set forth.

2. Mechanism for opening and closing a plurality of foldable doors, comprising a pair of rotatable vertical door or gate-supporting rods, a pair of foldably connected 105 door or gate-sections connected with each vertical supporting rod, a pair of brackets, a vertical shaft mounted in said brackets, a crank-lever upon the lower end-portion of said shaft, mechanism connected with the 110 upper end-portion of said shaft and with the upper end-portions of said supporting rods for simultaneously turning said rods and simultaneously operating the door or gate-sections connected with said supporting rods, consisting of a crank-arm affixed to said vertical shaft, a pair of adjustably connected plate-like members connected with one of said vertical supporting rods, a connecting rod between said crank-arm and said adjustably connected plate-like members, a second crank-arm affixed to said vertical shaft, a third bracket, a second pair of 115 adjustably connected plate-like members pivotally connected with said last-mentioned bracket, a connecting rod between said last-mentioned crank-arm and adjustably connected plate-like members, a third crank-arm also pivotally connected with said last-mentioned bracket, another crank-arm connected 120 with another one of said door or gate-sections, and a connecting rod between said two last-mentioned crank-arms, substantially as and for the purposes set forth.

- nected with the other of said vertical supporting rods, and a connecting rod between said two last-mentioned crank-arms, substantially as and for the purposes set forth.
- 5 3. The herein described mechanism for operating a plurality of door or gate-sections, comprising a pair of bearing-brackets, a vertical shaft mounted in said brackets, a crank-lever connected with said shaft, a buffer-plate upon one of said brackets, a crank-arm affixed to said vertical shaft, said crank-arm being adapted to be moved into arresting engagement with said buffer-plate, a pair of adjustably connected plate-like members connected with one of the door-sections, a connecting rod between said crank-arm and said adjustably connected plate-like members, a second crank-arm affixed to said vertical shaft, a third bracket, a second pair 10 of adjustably connected plate-like members pivotally connected with said last-mentioned bracket, a connecting rod between said last-mentioned crank-arm and adjustably connected plate-like members, a third crank-arm also pivotally connected with said last-mentioned bracket, another crank-arm connected with another door or gate-section, and a connecting rod between said two last-mentioned crank-arms.
- 15 4. The herein described mechanism for operating a plurality of door or gate-sections, comprising a pair of bearing-brackets, a vertical shaft mounted in said brackets, a crank-lever connected with said shaft, a buffer-plate upon one of said brackets, a crank-arm affixed to said vertical shaft, said crank-arm being adapted to be moved into arresting engagement with said buffer-plate, a pair of adjustably connected plate-like members connected with one of the door-
- 20 sections, a connecting rod between said crank-arm and said adjustably connected plate-like members, said connecting rod consisting of two members, said members being respectively provided with right and left internally screw-threaded sockets, and a rod-like member having right and left screw-threaded end-portions screwed into said sockets, a second crank-arm affixed to said vertical shaft, a third bracket, a second pair 25 of adjustably connected plate-like members pivotally connected with said last-mentioned bracket, a connecting rod between said last-mentioned crank-arm and adjustably connected plate-like members, 30 said connecting rod consisting of two members, said members being respectively provided with right and left internally screw-threaded sockets, and a rod-like member having right and left screw-threaded end-portions screwed into said sockets, a third crank-arm also pivotally connected with said last-mentioned bracket, another crank-arm connected with another door or gate-section, and a connecting rod between said 35 two last-mentioned crank-arms, said connecting rod consisting of two members, said members being respectively provided with right and left internally screw-threaded sockets, and a rod-like member having 40 right and left screw-threaded end-portions screwed into said sockets, substantially as and for the purposes set forth.
- 45 In testimony, that I claim the invention set forth above I have hereunto set my hand 45 this 22nd day of August, 1912.
- 50 EDWARD M. MOLLER.
